Primary Examiner—Mitchell Siegel

(57) **CLAIM**

The ornamental design for the multipurpose grille, as shown and described.

DESCRIPTION

FIG. 1 is a front elevation view of a multipurpose grille showing my new design; and,
FIG. 2 is a both sides edges view thereof.

The broken line showing is for illustrative purposes only and forms no part of the claimed design.

The surfaces or portions of the article not shown in the drawing or described in the specification forms no part of the claimed design.
